FIG. 23 is a left side view thereof;
 FIG. 24 is a top view thereof;
 FIG. 25 is a perspective view of a fifth embodiment of a slim gaming machine showing the new design;
 FIG. 26 is a front view thereof;
 FIG. 27 is a rear view thereof;
 FIG. 28 is a right side view thereof;
 FIG. 29 is a left side view thereof;
 FIG. 30 is a top view thereof;
 FIG. 31 is a perspective view of a sixth embodiment of a slim gaming machine showing the new design;
 FIG. 32 is a front view thereof;
 FIG. 33 is a rear view thereof;
 FIG. 34 is a right side view thereof;
 FIG. 35 is a left side view thereof;
 FIG. 36 is a top view thereof;
 FIG. 37 is a perspective view of a seventh embodiment of a slim gaming machine showing the new design;
 FIG. 38 is a front view thereof;
 FIG. 39 is a rear view thereof;
 FIG. 40 is a right side view thereof;
 FIG. 41 is a left side view thereof;
 FIG. 42 is a top view thereof;
 FIG. 43 is a perspective view of a eighth embodiment of a slim gaming machine showing the new design;
 FIG. 44 is a front view thereof;
 FIG. 45 is a rear view thereof;
 FIG. 46 is a right side view thereof;
 FIG. 47 is a left side view thereof;
 FIG. 48 is a top view thereof;
 FIG. 49 is a perspective view of a ninth embodiment of a slim gaming machine showing the new design;
 FIG. 50 is a front view thereof;
 FIG. 51 is a rear view thereof;
 FIG. 52 is a right side view thereof;
 FIG. 53 is a left side view thereof;
 FIG. 54 is a top view thereof;
 FIG. 55 is a perspective view of a tenth embodiment of a slim gaming machine showing the new design;
 FIG. 56 is a front view thereof;
 FIG. 57 is a rear view thereof;
 FIG. 58 is a right side view thereof;
 FIG. 59 is a left side view thereof;
 FIG. 60 is a top view thereof;
